ATTORNEY'S

UNITED STATES PATENT OFFICE.

EDWARD MCGAUGHEY TURNER, OF KNOXVILLE, TENNESSEE.

OIL-CAN PUMP.

SPECIFICATION forming part of Letters Patent No. 283,834, dated August 28, 1883.

Application filed March 3, 1883. (No model.)

To all whom it may concern:

Be it known that I, EDWARD MCG. TURNER, a citizen of the United States, residing at Knoxville, in the county of Knox and State of 5 Tennessee, have invented a new and useful Oil-Can Pump, of which the following is a specification, reference being had to the accompanying drawings.

This invention relates to pumps for oil-tanks 10 of that class which are used for dispensing kerosene and other oils; and it consists in certain improvements in the construction of the same, which will be hereinafter fully described, and particularly pointed out in the claim.

15 In the drawings hereto annexed, Figure 1 is a perspective view of my improved oil-can pump. Fig. 2 is a vertical sectional view, showing the pump in position for operation in an oil-can, parts of the pump-cylinders having 20 been broken away for the purpose of better illustrating the construction. Fig. 3 is a horizontal sectional view on the line *v v* in Fig. 2. Fig. 4 is a vertical sectional view on the line *x x* in Fig. 3. Fig. 5 is a vertical sectional 25 view on the line *y y* in Fig. 3, and Fig. 6 is a horizontal sectional view on the line *z z* in Fig. 2.

The same letters refer to the same parts in all the figures.

A in the drawings refers to the oil-tank in 30 which my improved pump is fitted. This tank is herein shown for the purpose of illustrating the arrangement and operation of my improved pump; but it is not herein claimed, as it will be made the subject of a separate application for Letters Patent.

35 B is the main pump-cylinder, which is provided at its lower end with a seat, C, for a ball-valve, D, above which is a cross-bar, E, to prevent the displacement of the said valve. The 40 upper end of cylinder B has a screw cap or cover, F, serving to hold in position an elastic packing disk or washer, G.

H is the piston or plunger which works in 45 the cylinder B. The piston is mounted upon a stem or rod, I, which extends upwardly through a perforation in the cap and washer, and is provided with a suitable handle, J.

K is a cylinder, secured adjoining the cylinder B, with which it is connected by an opening, L, at its lower end. The bottom of the

cylinder K is closed. Above the opening L it is provided with a seat, M, for a ball-valve, N, which is prevented from displacement by a cross-bar, O, arranged above.

P is a supplementary cylinder, arranged adjoining the cylinders B and K, and connected with the former by an opening, Q, near its upper end. The cylinder P is provided near its lower end, which is open, with a seat, R, for a ball-valve, S, above which a cross-bar, T, is arranged to prevent displacement. In the upper end of the cylinder P, above the opening Q, is a seat, U, for another ball-valve, V, which is likewise held in place by a cross-bar, W. It is not absolutely essential that the several 65 valves herein described should be ball-valves. Other valves of any suitable construction opening upward may be used with equally successful results; but I prefer ball-valves, as being more simple and less liable to get out of order than other differently-constructed valves. The upper ends of the cylinders K and P open into the discharge-pipe X, the upper end of which terminates in a bottle-spout, Y, having a ridge, Z, to prevent it from fitting too tightly 70 in the mouths of bottles and jugs that are to be filled, thus allowing the air to escape as the fluid passes in. The pipe X passes through and is firmly secured in a circular plate or disk, A², provided near its edge with a downwardly-projecting pipe, B², forming a flange, the lower end of which is connected by a brace, C², with the lower end of the discharge-pipe, as shown.

The "tray" D² of the oil-tank A is provided 85 with an opening, E², of sufficient size to admit the cylinders forming the pump and the pipe or flange B². The edge of the disk A² rests upon the upper edge of a screw-threaded collar F², surrounding the opening E², and is held in place by a screw-cap, G². Suitable packing may be interposed in order to make a tight joint.

H² is a tapering or conical brace secured on the under side of the tray surrounding the opening E². The lower end of this brace fits tightly against the flange or pipe B², thereby holding the pump steady during operation.

The operation of my improved pump will be readily understood from the foregoing de- 100

scription, taken in connection with the drawings hereto annexed. On the upstroke of the piston or plunger the lower end of the cylinder B is filled through the valve D, and fluid 5 is discharged from its upper end through the opening Q and valve V. On the downstroke of the piston fluid enters the cylinder P through the valve S, and passes from thence through the opening Q into the upper end of the cylinder B. At the same time fluid passes from the lower end of the latter through the opening L into the cylinder K, up through the valve N in the latter, and to the discharge-pipe.

This pump, it will be seen, is double-acting, 15 and will raise and throw a continuous stream of fluid. By simply dispensing with the supplementary cylinder P, a single-acting pump may be produced, which, being simpler and less expensive, may in some cases be found 20 preferable.

I claim as my invention and desire to secure by Letters Patent of the United States—

In an oil-can pump, the combination of the cylinders, constructed and arranged substantially as described, the discharge-pipe, the 25 disk or plate secured upon the latter, and provided near its edge with a downwardly-projecting flange, and a brace connecting the latter with the lower end of the discharge-pipe, as and for the purpose set forth.

In testimony that I claim the foregoing as my own I have hereto affixed my signature in presence of two witnesses.

EDWARD McGAUGHEY TURNER.
